WILLIS D. WITTER, OF CATONSVILLE, MARYLAND, ASSIGNOR, BY MESNE ASSIGNMENTS, TO AMERICAN LA FRANCE AND FOAMITE CORPORATION, A CORPORATION OF NEW YORK

FIRE EXTINGUISHER

Application filed April 9, 1925. Serial No. 21,804.

The invention relates to foam-type, self-contained fire extinguisher units of the kind adapted to be suspended over the area to be protected and to be set in action by some sort 5 of automatic release mechanism or otherwise, so as to produce the fire-extinguishing foam which falls and spreads over the burning surface. The invention consists in an improved extinguisher of this kind, in which 10 operation is brought about by the discharge of the foam-making solutions through passageways which are normally free from obstruction by valves likely to corrode or fragile diaphragms likely to leak and requiring 15 renewal, and in which the flow of the solutions is so governed that the initial discharge 20 is of foam of correct and predetermined quality and not liquid, and continues of this same quality until the action is completed, and in which also the discharge takes place quietly 25 and uninfluenced by the movement the extinguisher may have received by the agency which set it in action, and in which various other advantages are present as later made apparent.

Referring to the accompanying drawings,

Fig. 1 represents the extinguisher in side elevation in position suspended from the ceiling of a factory or room.

Fig. 2 is a larger scale, vertical axial section of the extinguisher in its normal position.

Fig. 3 is a cross section thereof in the same position.

Fig. 4 a similar section in the position of discharge, and

Fig. 5 is a broken out plan of the mixing chamber.

The two foam-making solutions are 40 respectively contained in the compartments produced by dividing the cylindrical sheet metal tank structure 1 by means of a transverse partition 2. The tank structure is journaled by gudgeons at its ends in the two open 45 journals 3 of the supporting enclosure or housing 4. The latter is provided with means 5 whereby it may be hoisted and suspended above the fire risk which may be, for instance, a dip tank or the like. The housing 4 protects the tank structure from injury by con-

tact with moving cranes or other objects in a factory, or if need be, from dust, in which case it is closed in on all sides except the bottom, suitable provisions being made whereby the top can be removed when it is 55 necessary to fill the compartments. In the present case the housing is shown open at top and bottom and is constituted by a main yoke or frame 6, to which the gudgeon journal 3 and the sheet metal panels which 60 constitute the side walls are attached. These panels are square and marginally reinforced so that the lower edge of the housing affords a stable support when lowered on to the floor and supports the tank, clear of the floor on 65 such occasions, thus facilitating the operation of filling the compartments. Obviously the side panels are not necessary for this function since the main frame member 6 could be made to serve the same purpose if necessary. 70 It is evident also that the apparatus, although intended primarily for suspension above the fire risk, could, where desirable, be operated when supported from the floor.

The tank structure rotates on its journal 75 axis to produce the discharge and mixture of the solutions, and for this purpose a mixing chamber 7 is secured to the wall of the tank which is normally uppermost. This chamber has communication, through two holes 80 cut in the tank wall, with each solution compartment and, on inversion, the solutions flow through these holes into the interior of the chamber mixing therein and producing the foam which emerges from the spout or mouth 9. The mixing chamber is elongated 85 in the direction of the solution movement therethrough and circumferentially around the tank, the spout mouth being thus circumferentially offset from the solution holes 8 so that time is given for the solutions to mix 90 and generate the gas by which the foam is produced. The mixing chamber thus forms, in the preferred and illustrated embodiment, a relatively shallow elongated conduit. By 95 extending the chamber circumferentially of the tank, or horizontally when the tank is inverted, the necessary length of mixing channel and time element referred to are obtained without materially increasing the 100

over-all vertical dimension of the apparatus. This, it will be understood, is important in devices of this kind which are intended to be suspended from the ceiling. It constitutes a feature of the present invention capable of adaptation to any suspended or overhead type of two-solution extinguisher. In the present case the interior of the mixing chamber is arranged with partition walls which direct the two solution streams into mutual impingement, thus promoting thorough mixture and prompt foam generation.

When the tank is in its normal position a cover cap 10 rests on and closes the spout mouth 9 and such cap is fastened to the housing by a chain or other loose connection so that as the tank rotates to discharge, and the mixing chamber swings downwardly, the spout mouth is separated from the cap, leaving the latter hanging free or against the side of the housing. The slack in the chain lets the spout gather downward headway before it parts from the cap, so that in the case of any possible sticking, the separation of the cap will be certain to be effected. Other means than a slack chain can obviously be arranged to produce the same effect.

Each solution compartment is provided with an inverted vent, constituted in the present case by a tube 11 fixed in the filling cap 12 of that compartment, so as to form a communication between the atmosphere adjacent the cap and the opposite interior side of the compartment. These tubes are normally covered by tethered closure caps 13, like the cap 10, so that when the tank has rotated to its discharge position the tubes are uncovered and in this inverted position, their inner ends will open above the solution levels and air will be admitted upwardly from the bottom side of the structure to maintain atmospheric pressure on both solutions. This venting is important to insure constantly equal or predetermined solution flow from the compartments to the mixing chamber and a uniform or steady flow is essential for producing foam of constant quality, i. e. containing no more of one solution than the other. Inasmuch as the vent tubes are secured to the filling caps, they are conveniently withdrawn out of the way when the latter are removed, as for charging.

In the apparatus illustrated, the journal axis of the tank structure in the housing or support is eccentric to its longitudinal axis so that being unbalanced it normally tends to swing or turn by gravity to its discharge position. The unbalanced weight of the mixing chamber which is a casting and correspondingly heavy, promotes this tendency, and in some conditions could be made heavy enough to turn the tank without the aid of the eccentricity. In the normal condition the tank is held from turning by a connection 14 to a heat-operated release mechanism repre-

sented generally by 15. This mechanism forms no part of this invention and may, if desired, be substituted by a chain having a fusible link such as common in this art, or the tank can be arranged to be released, or operated, by hand if that should be preferred.

It will be apparent that when the tank is released the effect is to lower slightly, by the amount of the eccentricity, the whole mass of the two solutions, but without producing any commotion in them, that is to say, the tank rotates with reference to the solutions and the mixing chamber outlet moves to the lower side of the solutions unaccompanied by any rotation or appreciable commotion of them. This is the effect of making the solution compartments cylindrical or substantially cylindrical and arranging the turning axis parallel to the cylindrical axis, by which is meant coincident with the cylindrical axis or equally spaced therefrom at all points, and results in the orderly and exactly coincident flow of each solution into the mixing chamber; this in turn results in developing foam of correct composition from the very beginning of the action.

The new organization in this respect constitutes an important departure from previous extinguishers of the suspended invertible type, wherein the solutions are likely to be much shaken by the inversion and the whole apparatus dangles and swings while discharging. The quiet and orderly operation of the present apparatus is insured in the present case by suspending the supporting structure or housing by means of three chains as indicated in Fig. 1 of the drawing, two of such chains being attached to the housing at the ends of the supporting yoke 6, or in the vertical plane of the rotation axis and the other to the center of the weighted side of the housing. By this method of support the whole structure is steady during discharge. The organization referred to has the further advantage that the solution capacity can be easily increased or varied according to different requirements, by increasing or changing the length of the tank and its support in the direction of the cylindrical axis, without requiring any change in the size of the other parts and without diminishing the head room below it.

It will be apparent, therefore, that the several principles involved in this invention can be jointly or severally incorporated in fire extinguishers of various forms, and it must be understood that there is no intended limitation to the illustrated combination of all of such features except as specifically provided in the following claims.

Claims:

1. A foam fire extinguisher of the kind adapted to be supported above a fire risk comprising in combination substantially cy-

lindrical solution compartments for component foam making solutions mounted for rotation as a unit on a horizontal axis parallel to the cylindrical axis to a discharging position, a mixing chamber and foam delivery conduit carried by said rotatable unit and having connections with each of said compartments and a foam delivery outlet, and means for retaining the unit in the position in which 5 said conduit is on the upper side thereof.

10 2. A foam fire extinguisher of the kind adapted to be supported above a fire risk, comprising in combination a rotatable substantially cylindrical unit having its axis 15 horizontal and provided with a plurality of receptacles for component foam making solutions, a mixing chamber and foam production and delivery conduit carried by the unit and extending circumferentially along the 20 outside of its cylindrical wall and having connections with each of the compartments above the solution levels therein, a foam discharge outlet from said conduit and means for rotating the unit on a horizontal axis parallel to its own to cause the solutions to flow 25 into said mixing chamber and delivery conduit for the production and delivery of foam.

3. A fire extinguisher of the kind adapted to be supported above a fire risk including a 30 rotatable unit overbalanced and thereby adapted to rotate for discharge on a horizontal axis, said unit comprising a plurality of adjoining cylindrical solution receptacles whose axes are parallel to and spaced from 35 the axis of rotation, a mixing chamber, inlets opening thereunto from each receptacle above the normal level of the solution therein, and a foam delivery outlet from the mixing chamber, and means for retaining the unit in overbalanced position.

40 4. A foam fire extinguisher of the kind adapted to be supported above the fire risk comprising two substantially cylindrical receptacles for the respective component solutions located end to end mounted to turn together on a horizontal axis parallel with the cylindrical axis to a discharge position, a mixing chamber for the production and delivery of foam forming part of the rotatable structure and to which each of the solution receptacles delivers its solution into contact with the other entering solution, and means for causing the rotation of the unit to discharge position in time of fire.

45 5. A foam fire extinguisher of the kind adapted to be supported above the fire risk comprising two substantially cylindrical receptacles for the respective component solutions located end to end and overbalanced to turn together on a horizontal axis parallel with the cylindrical axis to a discharge position, an elongated duct carried by the cylinder extending circumferentially thereof near 50 its cylindrical wall in the direction of dis-

charging movement and constituting a mixing chamber for the production and delivery of foam and to which each of the solution receptacles delivers, and means for retaining the unit in overbalanced position.

6. A foam fire extinguisher of the kind adapted to be supported above a fire risk comprising receptacles for component foam making solutions, an overhead supporting U-shaped structure open at the bottom and in which the receptacles are journaled for rotation from a normal to a discharge position, a mixing chamber and foam production and delivery conduit carried by and closely adjacent the cylindrical wall of the rotatable structure, inlets opening into the mixing chamber and foam production and delivery conduit from each receptacle, said supporting structure having protective means extending slightly beyond the dimensional limits of 70 said containers in their normal and discharge positions.

7. A foam fire extinguisher of the kind adapted to be supported above a fire risk including an overhead support and a unit rotatably mounted on said support on a horizontal axis and adapted to rotate for discharge, said unit comprising a plurality of solution receptacles, a relatively shallow and elongated conduit serving as a mixing chamber and for foam production and delivery, said conduit being in communication with said receptacles below the solution levels therein when the unit is in discharge position and extending lengthwise in a direction other than radial with respect to the axis of rotation of the unit and serving to conduct foam in a non-radial direction and having a foam delivery outlet through which it releases foam, and means for causing rotation 90 of the unit to discharge position in time of fire.

8. A foam fire extinguisher of the kind adapted to be supported above a fire risk including an overhead support and a substantially cylindrical unit rotatably mounted on said support with its axis horizontal and adapted to rotate for discharge on an axis parallel to its own axis, said unit comprising a plurality of adjoining solution receptacles whose axes are parallel to that of the unit, a relatively shallow and elongated conduit fitting the wall of the cylinder and extending lengthwise along it in a direction non-radial with reference to the axis of rotation, said conduit serving as a mixing chamber and for foam production and delivery, inlets opening into said conduit from each receptacle above the normal level of the solution therein, and a foam delivery outlet 100 from the said conduit, and means for causing the rotation of the unit to discharge position in time of fire.

9. A foam fire extinguisher of the kind adapted to be supported above a fire risk in-

cluding an overhead support and a unit rotatably mounted on said support on a horizontal axis and adapted to rotate for discharge, said unit comprising a plurality of solution receptacles, a relatively shallow and elongated conduit serving as a non-radial mixing chamber and for foam production and delivery, said conduit being in communication with said receptacles below the solution levels therein when the unit is in discharge position, and a foam delivery outlet from said conduit, pressure-equalizing means for the solution receptacles, and means for causing the rotation of the unit to discharge 15 position in time of fire.

10. A foam fire extinguisher including a support and a substantially cylindrical unit mounted on said support on a horizontal axis parallel to its own and adapted to rotate thereon for discharge, a partition between its ends intersected by said axis and forming separate compartments for mutually reactive foam making solutions, a conduit overlapping both said compartments, in communication with both and extending circumferentially along the cylinder wall and serving as a mixing chamber and for the production and delivery of foam.

11. A foam fire extinguisher including supporting means and a substantially cylindrical unit rotatable on a horizontal axis parallel to its own and having partition means dividing off from the interior thereof a plurality of compartments for component foam-making solutions, and comprising also a relatively shallow elongated conduit serving as a mixing chamber and for foam production and delivery and extending in a non-radial direction along the cylinder wall and adapted on rotation of the unit to discharge position to be in communication with said receptacles below the level of liquid therein, and having a foam discharge outlet to which said conduit conducts foam in a non-radial direction and through which it delivers foam.

12. A foam fire extinguisher comprising a horizontal cylindrical tank mounted to turn on an axis slightly offset with respect to its geometrical axis and normally below the same and adapted to be rotated for discharge, a transverse partition between and spaced from the ends of the tank and intersected by its axis and forming adjacent compartments for mutually reactive foam-making solutions, a mixing chamber secured to the outer face of the cylindrical wall of the tank overlapping both said compartments and in communication with both, and means for delivering foam therefrom.

13. A foam fire extinguisher comprising a horizontal cylindrical tank mounted to turn on an axis slightly offset with respect to its geometrical axis and normally below the same and adapted to be rotated for discharge, a transverse partition between and

spaced from the ends of the tank and intersected by its axis and forming adjacent compartments for mutually reactive foam-making solutions, a pressure equalizing tube on each side of said partition, a mixing chamber secured to the outer face of the cylindrical wall of the tank overlapping both said compartments and in communication with both, means for delivering foam from said mixing chamber, and means whereby said tank can be rotated for discharge.

In testimony whereof, I have signed this specification.

WILLIS D. WITTER.
